UNITED STATES PATENT OFFICE.

JOSEPH D. GALLAGHER, OF GLEN RIDGE, NEW JERSEY, AND HARRY JONES, OF SUFFERN, NEW YORK, ASSIGNEES TO AMERICAN BRAKE SHOE & FOUNDRY COMPANY, OF MAHWAH, NEW JERSEY, A CORPORATION OF NEW JERSEY.

COMPOSITION BRAKE-SHOE.

1,159,008.

Specification of Letters Patent. Patented Nov. 2, 1915.

Application filed May 4, 1915. Serial No. 25,685.

To all whom it may concern:

Be it known that we, JOSEPH D. GALLAGHER, a citizen of the United States, and a resident of Glen Ridge, county of Essex, 5 and State of New Jersey, and HARRY JONES, a citizen of the United States, and a resident of Suffern, in the county of Rockland and State of New York, have made and invented certain new and useful Improvements in Composition Brake-Shoes, of which the following is a specification.

This invention relates to composition brake shoes and has for its object to provide a shoe of this type which will be characterized by its long serviceable life and good frictional qualities, as heretofore, one of the objections to the use of composition shoes has been the relatively short serviceable life thereof and its excessively high frictional qualities.

A further object is to attain the aforementioned ends, that is, to lengthen the life of the shoe and reduce the frictional qualities thereof, in such manner that the various parts which go to make up the completed shoe are securely anchored together and reinforced throughout, so that should any of the parts become cracked or broken in service, they will not fall apart nor be come separated from the back of the shoe.

Other objects and advantages will appear as the description proceeds, wherein it is to be understood that changes in the precise embodiment of the invention can be made within the scope of what is claimed without departing from the spirit of the invention.

The preferred embodiment of our invention is disclosed in the accompanying drawings, wherein:—

Figure 1 is a view in perspective of our novel and improved brake shoe with portions of the composition body removed; Fig. 2 is a top plan view of the foregoing; and Fig. 3 is a view in section taken on the line 3—3 of Fig. 2.

The brake shoe, disclosed in the several views, comprehends a reinforcing back 5, which is provided with the integral and outstanding lug 6, whereby the shoe may be secured to a brake head or rigging in the usual and preferred manner. The back 5 is provided with the overturned side edges

7 and has the openings 8 extending lengthwise thereof and located upon opposite sides of the longitudinal center.

55

Temporarily anchored to the back, during the process of formation of the brake shoe, is the expanded metal or wire mesh cage 9, which is formed with the sides 10 and back 11. Hard metal end sections 12, are cast 60 upon the end portions of the steel back 5, the back and cage being placed on end within suitable molds, so that the resulting end sections are securely anchored to the back by means of the end stops 13, which are 65 formed by the cast metal flowing up, around, and embedding the ends of the back therein. The cast metal end sections 12 are extremely hard throughout and impart the requisite lasting or wearing properties to the shoe.

70

The wire mesh or expanded metal cage 9, in connection with the solid end sections 12, form a container for the reception and anchorage of the composition body 14. The wire mesh or expanded metal extends 75 throughout the entire length of the hard metal end sections and reinforces the same, so that should portions thereof become broken or fractured in service, such parts will not become separated from the back of 80 the shoe.

The hard metal end sections, as illustrated in Fig. 1, are provided with the confronting depressions or recesses 15, which, in connection with the undercut or beveled end walls 16, serve to securely anchor and retain the composition body 14 in position. The composition body 14 is forced into the interstices of the expanded metal or wire mesh of the cage and into the confronting 90 recesses 15 of the hard metal end sections, and, as illustrated in Fig. 3, up through the openings 8 in the shoe back, so as to terminate flush with the upper surface thereof. In this manner, the composition body is 95 rigidly anchored to the reinforcing back of the shoe and to the hard metal end sections by the expanded metal or wire mesh, which latter, extending through the composition body, reinforces and binds the same together.

100

The composition body 14 is formed of any suitable substance or mixture of ingredients which possess the proper frictional qualities. One of the objections heretofore raised

against the use of composition shoes, was the relatively short useful life thereof, and excessively high frictional qualities. In the present shoe, a long and serviceable life has been provided for and the frictional qualities have been decreased, the same being accomplished by reason of the hard metal end sections which lend the requisite wearing or lasting qualities to the shoe and necessarily prevent too great a pressure between the composition body 14 and the car wheel, so that only the proper and moderate amount of friction results.

What we claim is:—

15. 1. A brake shoe comprising in part a container having a back, and depending sides of open metalwork, and continuous metal ends, said container adapted to receive and contain a portion of the body of the shoe.
20. 2. A brake shoe comprising in part a container having a back, and depending sides of expanded metal, and continuous metal ends, said container adapted to receive and contain a portion of the body of the shoe.
25. 3. A brake shoe comprising in part a container having a back and depending sides of open metalwork, and continuous or solid metal ends, said container adapted to receive and contain a composition body.
30. 4. A brake shoe comprising in part a container having a back and depending sides of expanded metal, and continuous or solid metal ends, said container adapted to receive and contain a composition body.
35. 5. A brake shoe constructed with a container having a back and depending sides, and solid metal ends provided with depressions, said container and depressions adapted to receive and contain a composition body.
40. 6. A brake shoe constructed in part of a container having depending sides of open metalwork, and with solid hard metal ends provided with depressions, said container and depressions adapted to receive and hold a composition body.
45. 7. A brake shoe formed with a container having a back and depending sides, and solid metal ends, said ends provided with confronting depressions for the reception and retention of a composition body.
50. 8. A brake shoe comprising hard metal end sections, and a cage of open metalwork

extending therebetween, and a composition body anchored thereto. 55

9. A brake shoe comprising a cage with a back and depending sides formed of open metalwork, hard metal end sections anchored to said cage, and a composition body disposed between said hard metal ends and anchored to said cage.

10. A brake shoe comprising a reinforcing back, a cage of open metal work extending lengthwise thereof, hard metal end sections anchored to said reinforcing back and to 65 said cage, and a composition body extending between said hard metal ends and anchored to said cage and reinforcing back.

11. A brake shoe including spaced hard metal end sections, a cage of open metalwork 70 embedded therein and extending therebetween, said end sections provided with confronting recesses, and a body possessing high frictional qualities anchored to said cage and extending within said depressions. 75

12. A brake shoe including spaced hard metal end sections, a cage of expanded metal embedded therein and extending therebetween, said end sections provided with confronting recesses, and a body possessing 80 high frictional qualities anchored to said cage and extending within said depressions.

13. A brake shoe comprising a reinforcing back, a cage including a back and side walls of openwork metal and extending lengthwise of said brake shoe back, hard metal end sections anchored to said back embedding said cage therein and reinforced thereby, said end sections and cage forming a container, and a composition body carried by 90 said container and extending between said hard metal end sections. 85
